Everett K. Wolfe

By his Attorney

Walton Harrison.

UNITED STATES PATENT OFFICE.

EVERETT K. WOLFE, OF WESTCHESTER, NEW YORK.

SOAP-HOLDER.

1,337,535.

Specification of Letters Patent.

Patented Apr. 20, 1920.

Application filed November 22, 1918. Serial No. 263,703.

To all whom it may concern:

Be it known that I, EVERETT K. WOLFE, a citizen of the United States, residing at Westchester, in the county of Bronx and 5 State of New York, have invented a new and useful Soap-Holder, of which the following is a full, clear, and exact description.

My invention relates to soap holders of a 10 kind suitable for use in connection with a bath-tub of the ordinary kind, my more particular purpose being to enable a bar of soap to be held upon the rail or side portion of the bath-tub so that the bar of soap 15 will not readily slip off.

More particularly stated, I provide a soap holder having generally the form of a pad, and made with a rough surface so that when rested upon the rail of the bath-tub the bar 20 of soap may be simply rested on the pad and will there remain secure until picked up by the operator.

My invention further contemplates placing advertising matter upon the pad, and 25 the provision of end borders for preventing the adjacent portions of the pad from fraying or becoming unsightly. My invention further contemplates provision for enabling the soap holder to be readily suspended 30 from a nail or pin or to be rolled up or folded, as desired.

As my invention may assume different forms, I will describe a few such forms as typical of the construction.

Reference is made to the accompanying 35 drawing forming a part of this specification, and in which like letters indicate like parts throughout the various figures.

Figure 1 is a plan view of one form of 40 my soap holder.

Fig. 2 is a section on the line 2—2 of Fig. 1, looking in the direction of the arrows.

Fig. 3 is a plan view of a slightly different form of my invention.

Fig. 4 is a section on the line 4—4 of Fig. 45 3, looking in the direction of the arrows.

Fig. 5 is a fragmentary section showing another form of the invention, in which the end piece is secured in position somewhat 50 differently from that disclosed in Figs. 1 to 4 inclusive.

Fig. 6 is a fragmentary section showing still another form of my device, the difference relating to the manner in which the end strip is secured in position. 55

Fig. 7 is a fragmentary section through a bath-tub showing the manner in which my invention is used.

In the form shown in Fig. 1 a body member 8 is made of cloth preferably rough, as 60 indicated by stippling, and provided with end portions 9, 10. The pad is provided with advertising matter, such as the picture 11 and the legend 12. The ends of the pad are provided with end strips 13, 14, which 65 may be of sheet metal such as brass, German silver, aluminum, or even steel. If desired, however, these end strips may be made of celluloid, hard rubber, or even leather, cloth or paper of suitable texture. The end strip 70 13 is provided with an ear 15 preferably integral with it, as shown.

In the form shown in Figs. 3 and 4, the body member appears at 16 and is provided with end portions 17, 18, integral with it. 75 These end portions carry end strips 19, 20, which like the end portions 13, 14 above described, are each of arcuate form. The end strip 19 is provided with a hole 21 which is used in hanging the pad from a nail or the 80 like.

In the form shown in Fig. 3 the pad is provided with advertising matter such as the picture 22 and the legend 23, associated therewith. 85

In the form shown in Fig. 5 the body of the pad appears at 24 and one of the end strips at 25. In this instance the end strip is clenched so as to compress the inclosed portion of the pad. 90

In the form appearing in Fig. 6 the body of the pad appears at 26 and one of the end strips at 27, the latter having a portion 28 which is bent over and pressed into the adjacent portion of the pad. 95

In the material used for the pad the operator can exercise considerable discretion. That is to say, the material employed may be of various kinds. It may be woven or knitted fabric of any kind or it may be felt 100 or matted material of any sort suitable for the purpose. In some instances it may be

even made of tough paper of a texture suitable for the purpose and having a rough surface.

A bath-tub is shown at 29 and a bar of soap at 30 in Fig. 7.

The operation of my device may be readily understood from the foregoing description. The soap holder is rested upon the rail of the bath tub, one of the end portions 10 hanging inside of the tub and the other hanging outside, as indicated in Fig. 7. The bar of soap being now rested upon the middle portion of the soap holder, it is unable to slip off the rail of the bath tub. Advertising matter carried by the soap holder 15 attracts the attention of the operator in a casual way and, on this account, the device possesses more or less added value as an advertising medium.

The soap holder as a whole may be manufactured in quantity and sold as a commodity, or it may be used by hotels and the

like for the convenience of guests, or it may be employed solely as a medium of advertising. I do not limit myself to any particular use for the invention.

I claim:—

1. A soap holder comprising a body member made of flexible sheet material and having an exposed surface bearing advertising matter, said body member having a middle portion to be rested upon the rail of a bath tub, and a pair of end portions to hang upon opposite sides of said rail, said middle portion being sufficiently rough to support a 35 cake of soap resting thereon.

2. A soap holder comprising a body member made of flexible material and having two end portions and a middle portion, said middle portion having a surface to which a 40 cake of soap, resting thereon, will slightly adhere.

EVERETT K. WOLFE
